PRINTING MACHINE

Commodore D. Ryan, Los Angeles, Calif., assignor
to National Postal Meter Company, Los Angeles,
Calif., a corporation of California

Application April 15, 1935, Serial No. 16,435

5 Claims. (Cl. 101—91)

This invention relates to a printing machine of the multi-denomination postage printing type and, more particularly, to means for locking the casing door of the machine closed until the value printing means has been actuated to a non-printing position with relation to the printing head of the machine.

To prevent fraudulent tampering with the operating mechanism of a postage printing machine, it has been customary to seal such mechanism within a suitable casing and to provide a doorway through which access may be had to the printing die for the purpose of removing the date circle for changing the date type thereof. Also, the doorway is arranged to permit the removal or replacing of the usual ink pad.

When equipping such a machine with a multi-denomination printing head arranged to print stamps of relatively high values, it has been found advisable to provide means for preventing an attempt being made to obtain a fraudulent printing of postage, as for example on gummed tape, by projecting such tape through the doorway and bringing the same against the printing surface of the printer head.

It is, therefore, one of the principal objects of this invention to provide a locking system which is operatively connected to the denomination selector means whereby the casing door will be maintained securely locked at all times during the normal operation of the machine and may be unlocked only when the selector means has been shifted to actuate the multi-denomination printing means to a non-printing position. When the parts are so positioned, the casing door may be easily opened for either changing the date printing type in the date circle printing die or for replacing or re-inking the usual ink pad of the machine. As the denomination printing means is turned to a non-printing position when the casing door is permitted to be opened, it will be impossible to obtain from the machine the printing of a fraudulent postage stamp.

It is a further object to provide the machine with locking means for the driving mechanism thereof, also operatively related to the selector means, whereby the machine will be locked against use when the selector means has been shifted to such position as to unlock the casing door. By this arrangement, it will be appreciated that when the casing door is unlocked it will be impossible to operate the driving mechanism of the machine in an attempt to bring the

printer head down to a position from which an impression may be taken.

A further object is to arrange the multi-ratio connection with the selector means in such a way as to render this means inoperative to drive the adding and subtracting registers of the machine while the selector means is in position to release or unlock the casing door, thus further protecting the machine against improper operation.

A further object is to provide a multi-denomination postage printing machine which cannot be used for fraudulently printing postage stamps upon gummed or other forms of narrow material which may be inserted through the casing door.

Other objects and advantages of the invention will become apparent as the nature of the same is more fully understood from the following description and accompanying drawings, wherein is set forth what is now considered to be a preferred embodiment. It should be understood, however, that this particular embodiment of the invention is chosen principally for the purpose of exemplification and that variations therefrom in details of construction or arrangement of parts may accordingly be effected and yet remain within the spirit and scope of the invention as the same is set forth in the appended claims.

Figure 1 illustrates a side elevational view, partially in section, of the printing machine having the safety means of this invention incorporated therein.

Figure 2 illustrates a fragmental plan view of Fig. 1, partially in section to show the structural details of the locking means for the casing door.

Figure 3 illustrates an enlarged fragmental side view of the safety means positioned to unlock the casing door.

Figure 4 illustrates a view similar to Fig. 3 but showing the casing door open.

Figure 5 illustrates an enlarged sectional view of the adding and subtracting meters together with their multi-ratio driving means.

Figure 6 illustrates a schematic sectional view of the multi-ratio driving means; and

Figure 7 illustrates a perspective view of the main driving mechanism of the machine and the selector actuated locking means therefor.

The multi-denomination postage printing machine illustrated in the drawings is generally of the type shown and described in the application for United States Letters Patent, Serial No. 732,270, filed June 25, 1934, by Frank P. Sager

and Ernest R. Bergmark, differing therefrom, however, in that the printing machine shown herein for the purpose of illustration is of the power driven type, whereas the machine of the application above referred to is a hand operated machine. It will be understood, however, that the invention set forth herein may be just as readily adapted to machines of either the hand driven or power driven types.

The printing machine is organized in a compact unit having a suitably formed base casting 11 to which the several elements of the machine are appropriately mounted. The base casting includes a solid bottom partition 12, a rear wall 13, an intermediate standard 14, and a pair of front standards 15 for supporting the parts of the machine later to be described.

Printing head

The machine includes a printing head 16 and, as may be observed in Figure 1, the printing head 16 is suitably mounted upon the forward end of a pair of swing arms 17, as by means of screws 18. The rear ends of the swing arms may be journaled upon a transverse shaft 19, which shaft may be suitably supported in the forwardly extending brackets formed upon the front face of the base casting rear wall 13. An ordinary spring means, not shown, may be provided for yieldingly urging the printing head to its elevated position as illustrated in Figures 1, 3, and 4.

The printing machine is provided with a driving mechanism, later to be described, which is operable for swinging the printing head into printing relation with mail matter placed upon the resilient platen 21, which platen is suitably mounted upon the forward end of the base casting 11. The face of the printing head may be provided with a stamp printing die 22 and a date circle printing die 23.

The printing head is provided with a multi-denomination printing means 24 which includes a rotatable member 25 journaled therein and which rotatable member is provided upon an appropriate portion of its periphery with value printing dies 26 so arranged that any one of these dies may be turned into a printing position, in which position they will coincide with the printing face of the stamp printing die 22 and for this purpose the stamp printing die is provided with a suitable opening 27 through which the die portion of the rotatable member may project.

The rotatable member is provided with four value printing dies 26 of the following values, 2, 3, 5, 8, and 10, but it is to be understood that any other selection of values may be made.

In Figure 1, the rotatable member 25 is shown positioned to bring the 2 cent printing die into printing position with relation to the stamp printing die 22; while in Figure 3 the multi-denomination printing means is shown turned to a non-printing position.

A selector means is provided for selectively positioning the printing die 26.

Selector means

The selector means may include a selector lever 28 journaled on the stub shaft 29, and operatively connected to the selector rack 30 by means of link 31. The link 31 is pivotally connected at one end to the selector lever by pivot pin 31a and at its other end to rack 30 by a pivot pin 31b, (Figs. 1 and 3). The selector rack may be slidably mounted upon one of the swing arms 75 and provided at its forward end with a slot 32

through which a pin 33 may project to slidably support the forward end of the rack. The under surface of the forward end of the rack may be provided with a plurality of rack teeth 34 meshing with the multi-denomination printing means 5 pinion 35.

By the mechanism just described, the multi-denomination printing means may be rotated to bring any one of its printing dies into printing position.

Means are provided for correctly positioning the selector lever for each value of the multi-denomination printing means.

In the machine illustrated, the selector positioning means may include a positioning pawl 15 36 pivotally fastened to the machine frame as by means of pivot pin 37 and carrying at its forward end an arcuate positioning comb 38 having a well rounded depression 39 for each value of the multi-denomination printing means. The 20 positioning comb is adapted to cooperate with a roller 40 journaled upon the side face of the selector lever and is yieldingly urged into operative relation with roller 40 by suitable spring means 41.

It will be understood that the positioning comb does not lock the selector lever in any one of its printing positions, merely acting to correctly locate this lever in order that the selected value printing die will be positioned in a correct printing position with relation to the stamp die 22. The selector lever 28 may be swung from its position as illustrated in Fig. 1 to any one of its three other positions. In swinging from any one position, the roller 40 will ride out of its related depression 39 causing the positioning comb to be lifted against the action of spring 41. Figure 3 illustrates the selector lever substantially midway between the first and second positioning comb depressions 39 and illustrates the 40 comb in its elevated position. The tension of spring 41 is sufficient to cause the selector lever to be swung until its roller 40 will ride into the bottom of the nearest depression should the selector lever be released before arriving at that 45 position, thus insuring a more or less automatic and positive positioning of the selector lever and thereby the automatic positioning of the selected printing die in its correct printing position. It is necessary to register the value of each stamp 50 printed and, therefore, a suitable register is provided for this purpose.

Register

In the embodiment of the invention illustrated 55 in the drawings, the machine is provided with an adding register 42 and a subtracting register 43, (Figs. 1, 5, and 6). These registers are operated during the printing cycle of the machine to register therein the value of the stamp printed and are of the usual construction commonly found in this form of machine, and as no claims are addressed thereto it is not deemed necessary to describe the registers in detail other than to state with each actuation of the machine the 65 value of the stamp printed will be added to the value registered in the adding register and subtracted from the value previously registered in the subtracting register.

It is necessary, however, to provide a multi- 70 ratio driving means operable for establishing a driving connection between the driving mechanism of the machine and the registers proportional to the value of the stamp being printed, as for example, in printing a 2 cent stamp 75

the multi-ratio driving means will be automatically positioned to add to the adding register two units and to subtract from the subtracting register a like quantity; and when printing a 10 cent stamp to add and subtract this value from the respective registers. The adding and subtracting registers are driven from the main shaft 44 of the driving mechanism of the machine. The driving connection from the shaft to the register includes the multi-ratio driving means and, as this mechanism is substantially identical for each of the registers, the description thereof will be limited to one, namely, to the adding register.

Referring particularly to Fig. 6, it may be observed that the main shaft carries a driving pinion 45 meshing with a driven gear 46 carried by a sleeve 47, which sleeve is journaled upon the shaft 48 of the adding register. The sleeve is provided with a keyway 49 having securely mounted therein a suitable driving key. Slidably mounted on the sleeve 47 is a sleeve 50 which is considerably shorter than the main sleeve 47 and is provided with a keyway cooperating with the key means of the main sleeve so as to be driven thereby and yet to be slidable thereon.

Suitably fastened upon the periphery of the second ratio sleeve 50 are four ratio gears 51a, 51b, 51c, and 51d. The ratio gear 51a may be provided with two teeth, gear 51b with three teeth, gear 51c with eight teeth and gear 51d with ten teeth.

Each of the ratio gears above referred to is also provided with a locking surface 52a, 52b, 52c, and 52d. In parallel relation to the register shaft 48 is a counter shaft 53 having fastened thereto a ratio pinion 54. Also fastened upon shaft 53 is the units wheel driving pinion 55 maintained in continuous driving mesh with the units wheel driven gear 56.

The ratio pinion 54 is provided with a locking disc 58 which cooperates with the respective locking surfaces 52a, 52b, 52c, and 52d of the respective ratio wheels to prevent rotation of the ratio pinion until the gear teeth of the respective ratio gears reach the ratio pinion during the operation of the machine. In this way, the units wheel of the register will be locked against turning except by the driving action of the ratio gears and also the teeth of the driven pinion will be maintained in position to mesh with the teeth of the related ratio gear during the operation of the machine.

It will be necessary, of course, to bring the correct ratio gear into driving relation with the ratio pinion for the printing of a stamp of selected value and for this reason the ratio gears are made to slide longitudinally with relation to the ratio pinion 54, thereby serially bringing any one of the ratio gears into mesh therewith. It is only necessary, therefore, to provide means operatively connected to the selector lever for shifting the ratio sleeve 50 in proportion to the movement of the lever when selecting a value for printing.

The operative connection between the selector lever and the ratio sleeve 50 may include providing a reciprocatory shaft 59 located parallel to the register shaft 48 and slidably mounted in the register in any suitable manner.

A crosshead 60 may be fastened upon shaft 59 and arranged to engage the annular groove 61 formed in the end of the ratio sleeve to provide a rotatable connection between the sleeve and

crosshead and yet providing a connection which will cause the ratio sleeve to slide in direct ratio to the motion of shaft 59.

As may be observed in Fig. 1, shaft 59 is provided with a depending arcuate finger 62 closely fitting a correspondingly shaped depression 63 formed in the free end of a lever arm 64 fastened upon a transverse shaft 65. The outer end of shaft 65 may be provided with a lever 66 having its free end operatively connected to the selector lever 28 by means of link 67, as may be observed in Figure 3. Through this connecting mechanism it will be appreciated that a movement of the selector lever will be transmitted to slide the ratio sleeve proportionately, thus when the selector lever is positioned in its 2 cent position the ratio gear 51a having two teeth will be shifted into driving alignment with the ratio pinion 54. When the selector lever is shifted to the 3 cent position, the ratio gear 51b having three teeth will be shifted into driving alignment with the ratio pinion 54 and so on for the other positions of the selector lever. Thus, it will be appreciated, that with the actuation of the selector lever to any one of its positions will correspondingly set the multi-denomination printing means and the multi-ratio driving means to print and register the selected value of stamp when the machine is actuated through a printing cycle.

30

Driving mechanism

The driving mechanism of the machine may include the main drive shaft 44 suitably journaled in the base casting 11 and may be provided at its forward end with a crank arm 68, while the printing head 16 may be provided with a cam blade 69 having a cam groove 70 of appropriate shape cooperating with a roller 71 carried by the free end of the crank arm for driving the printing head into printing engagement with mail or other matter placed upon the resilient platen 21.

It will be understood that one rotation of the main shaft 44 will bring about one complete printing and registering cycle of the machine.

It is desirable to provide the machine with means for locking the main shaft against rotation and thereby the printing and registering means during the actuation of the selector lever 28 from one printing position to the next. For this purpose the rear end 72 of positioning pawl 36 is provided with a more or less circular knob 73 arranged to cooperate with a suitable opening 74 formed intermediate the ends of the locking pawl 75, which pawl at one end may be journaled upon the rear wall 13 of the machine by pivot means 76, while the forward end of the pawl may have a downwardly projecting tooth 77 directly overlying the locking notch 78 of the locking cam wheel 79, which wheel is securely fastened upon the main shaft 44. The position of the parts, as shown in Figure 7, illustrates the machine at rest. With the parts in the position shown, a movement of the selector lever from any one of the positioning notches 39 will cause the locking comb 38 to be raised as shown in Figure 3, bringing about a corresponding depression of the rear end of the positioning pawl and through its connection with the locking pawl will cause tooth 77 thereof to be forced into locking engagement 70 with the cam wheel 79, thus preventing operation of the machine until the selector lever has been shifted to its selected printing position, whereupon the positioning pawl 36 will return to its normal position under influence of spring 41.

55

60

65

70

75

80

85

90

95

thereby lifting the locking tooth 77 clear of the locking cam wheel 79, thus freeing the machine for operation.

The extreme rear end of the main drive shaft 44 may be provided with one member 80 of an Oldham coupling, by which means the printing machine may be connected and driven from a suitable source of power such as disclosed in the United States Letters Patent to John Q. Finn, No. 1,988,036, dated January 15, 1935, titled "Power plant".

To prevent fraudulent tampering with the printing dies or register, the operating mechanism and the several elements of the machine are inclosed within a casing 81. It will be understood that the casing 81 is locked to the base casting 11 in any suitable manner, not shown. The casing is provided with a slotted opening 82 (Fig. 2) through which the upper end of the selector lever may project. The main drive shaft 44 of the machine extends through the rear end of the casing to provide a driving connection exterior thereof and the casing is provided with a transverse opening 83 directly above the resilient platen 21 to permit the placing of mail matter in printing position.

To permit access to the date circle die of the printing head and to the ink pad, not shown, the side of the casing is provided with a more or less rectangular opening 84, as may be clearly seen in Figs 1, 3, and 4. A door 85 is provided for normally closing opening 84. The door is mounted within the casing and is hinged therein by a suitable hinge pin 86 to the side of front standard 15. Projecting forwardly from the door is a handle 87 by means of which the door may be readily opened. When the printing machine is to be used for the printing of postage stamps of various values, it has been found advisable to provide means which automatically lock the casing door closed until the multi-denomination printing means is turned to its non-printing position as illustrated in Fig. 3. In other words, the casing door will be locked closed whenever any one of the several printing dies are in printing position and will only be unlocked to admit entrance to the machine when the multi-denomination printing means is turned to its non-printing position. As the multi-denomination printing means is turned to its non-printing position by its selector lever 28, it also follows that the multi-denomination ratio driving means will be shifted to an inoperative position whenever the selector means is positioned to release the door for opening.

Casing door

The casing door locking means may include providing a swinging gate 88 which is securely fastened to the end of shaft 65 upon the door side of the casing. The gate member is provided with a slot 89 positioned to register with the projecting pin 90 (Fig. 2), which is carried upon the free end of link 91. The opposite end of link 91 may be pivotally connected to the casing door as by means of pivot pin 92. The free end of link 91 is supported and guided by a diagonal plate 93. The diagonal plate extends from the corner bracket 94 adjacent the upper end of standard 15 of the base casting, and is fastened thereto by suitable screw means 95. This plate is provided with a guideway 96 in which the head 97 of the projecting pin 90 is adapted to slide.

To provide a further support for pin 90, a

reinforcing plate 98 may be fastened to plate 93 as by rivets 99 and is suitably spaced from the plate, as may be observed in Fig. 2, whereby the gate and related end of link 91 may be positioned between plates 93 and 98.

The plate 98 is provided with a guideway 100 for guiding and supporting the free end of pin 90.

As may be noted in Fig. 1, when the selector lever is positioned to place the 2 cent printing die in printing position, the pin 90 will engage the periphery of gate 88 and will thereby lock the casing door against opening.

Should it be attempted to open door 85, the link 91 will thrust the pin 90 against the peripheral edge of the gate 88, thus securely locking the door against being opened. If, however, the selector lever is moved as illustrated in Fig. 3, that is in position substantially midway between the 2 cent and 3 cent selector positions, the gate slot 89 will then register with the guideways 96 and 100 of plates 93 and 98.

The opening of the door will cause the pin 91 to travel along the guideways 96 and 100 and into the gate slot 89. It should be remembered that this particular position of the selector lever has actuated the multi-denomination printing means to its non-printing position, has rendered the multi-ratio driving means inoperative and has caused the locking pawl 75 to lock the main drive shaft and thereby the machine against use. Thus it will be appreciated that the machine is fully protected against mis-use when the casing door is unlocked.

If the selector lever 28 is shifted to any other position, the peripheral edge of the gate member 88 will prevent the pin 90 from sliding along its guideways 96 and 100 and thus securely lock the casing door closed.

In order to correctly position the selector lever for unlocking the door, casing 81 adjacent the selector slot 83 may be provided with index means 101. Also, upon the casing adjacent the slot for correctly positioning the selector lever are index numbers 2, 3, 8, and 10, which indicate the value of stamp which will be printed by the machine should the selector lever be placed opposite any one of these figures.

Although the multi-denomination printing and multi-ratio driving means have been illustrated for a four place machine; that is a machine capable of printing four denominations, it will be understood that a machine may be built for a lesser or greater number of denominations.

It is to be understood that in some cases it may be advisable to unlock the casing door when a multi-denomination printing die of nominal value such as one, two or three cents is in printing register as in such case it would not be worth the trouble and risk to attempt to obtain a fraudulent stamp.

Having fully described a preferred embodiment of the invention, it is to be understood that it is not to be limited to the details herein set forth but the invention is for the full scope of the appended claims.

I claim:

1. In a multi-denomination printing machine, a printer head, multi-denomination printing means carried thereby and operable for presenting a single value at the printing position for each printing operation, selector means operable for actuating the multi-denomination printing means to bring the selected value into printing position, casing means inclosing the machine and having an opening for permitting access to the printer

head, a door for closing the casing opening, and means for locking the door closed, and means actuated by the selector means when the selector means is actuated to position the multi-denomination printing means in a non-printing position for releasing the door locking means.

2. In a multi-denomination printing machine, a printer head, multi-denomination printing means carried thereby and operable for presenting a single value at the printing position for each printing operation, selector means operable for actuating the multi-denomination printing means to bring the selected value into printing position, a first locking means associated with the selector means for locking the machine against use during the operation of the selector while actuating the multi-denomination printing means from one value to the next, casing means inclosing the machine and having an opening for permitting access to the printer head, a door for closing the casing opening, and a second locking means associated with the selector means for locking the door closed until the said selector means is shifted to bring the multi-denomination printing means to a non-printing position and the first locking means into action for locking the machine against use.

3. In a multi-denomination printing machine, a driving mechanism for the machine, a printer head driven thereby, multi-denomination printing means carried by the printer head and operable for presenting a single value at the printing position for each printing operation, selector means operable for actuating the multi-denomination printing means to bring the selected value into printing position, locking means associated with the selector for locking the driving mechanism whenever the multi-denomination printing means is moved from any one of its correct printing positions, casing means inclosing the machine and having an opening for permitting access therein, a door for closing the casing opening, stop means

operatively associated with the door, gate means operatively associated with the selector for opposing the stop means and to thereby lock the casing door, said gate being operable to release said stop for unlocking the door when the selector is shifted to move the multi-denomination printing means to a predetermined non-printing position in which position of the selector the aforementioned locking means will act to lock the machine against use.

4. In a multi-denomination printing machine, a printer head, multi-denomination printing means carried thereby and operable for presenting a single value at the printing position for each printing operation, selector means operable for actuating the multi-denomination printing means to bring the selected value into printing position, casing means inclosing the machine and having an opening for permitting access to the printer head, a door closing said casing opening, stop means operatively associated with the door, gate means operatively associated with the selector and opposed to said stop for locking the door closed until the selector is shifted to bring the multi-denomination printing means to a predetermined non-printing position.

5. In a multi-denomination printing machine, a printer head, multi-denomination printing means carried thereby and operable for presenting a single value at the printing position for each printing operation, selector means operable for actuating the multi-denomination printing means to bring the selected value into printing position, casing means inclosing the machine and having an opening for permitting access to the printer head, a door for closing the casing opening, and means for locking the door closed, and means actuated by the selector for releasing the door locking means when said selector is actuated to a predetermined position.

40
COMMODORE D. RYAN.
